UNITED STATES PATENT OFFICE.

ISAAC LOW, OF EAST FAIRFIELD, OHIO.

CAR-COUPING.

SPECIFICATION forming part of Letters Patent No. 602,342, dated April 12, 1898.

Application filed October 27, 1897. Serial No. 656,538. (No model.)

To all whom it may concern:

Be it known that I, ISAAC LOW, a citizen of the United States, residing at East Fairfield, in the county of Columbiana and State of Ohio, have invented certain new and useful Improvements in Car-Couplings; and I do hereby declare the following to be a full, clear, and exact description of the invention, such as will enable others skilled in the art to which it appertains to make and use the same.

This invention has reference to a novel construction in a car-coupling, the object being to provide a coupling in connection with which the ordinary link is used, but which couples automatically.

The invention consists in the features of construction hereinafter described and specifically claimed.

In the accompanying drawings, forming part of this specification, Figure 1 is a vertical longitudinal section of a coupler constructed in accordance with this invention. Fig. 2 is a transverse vertical section with the coupling-pin elevated. Fig. 3 is a similar view with the coupling-pin at the lower limit of its movement.

Referring now to said drawings, 1 indicates the draw-bar, and 2 the draw-head, which are of any approved construction in their general structural features. The upper side of the draw-head is open, while in the lower wall of the draw-head is a slot 3 to receive the lower end of the pin 4. This coupling-pin 4 is provided with an enlargement 5, forming downwardly-facing shoulders 6, that are adapted to rest upon the link 7, as shown in Fig. 3, for the purpose of holding the link in a horizontal position.

At the rear end of the draw-head is the outwardly-extending projection 8, having an inclined front face that forms a rest or support for the coupling-pin when the latter is elevated. At each side of the draw-head and at the rear end thereof are the notches 9, that form bearings for the pivoted bar 10. This bar 10 is provided at its ends with a journal resting in said bearings and is also provided with arms 11, to the outer ends of which the

coupling-pin 4 is pivoted. At one end of the pivoted bar 10 is the handle 12 for turning 50 the same.

The link 7 is provided on its lower side and midway between its ends with the lugs or pins 13, while the edge of the lower wall of the coupler is formed with recesses 14 to receive 55 the said pins 13. The rear wall of the cavity of the draw-head is provided with a socket 17 to receive the end of the link, and which serves to hold said link in a horizontal position even when the coupling-pin is not resting 60 thereon.

It is seen from the foregoing description that the pin can be raised or lowered by means of the handle 12 and that in coupling automatically said pin can be raised until it 65 rests against the upright or support 8. In this position it stands at an inclination with the lower end of the pin high enough to permit the link to enter, while the impact between the couplers on the two cars as they 70 come together in coupling will throw the pin forward, so that it falls through the link and the slot 3 in the bottom of the draw-head.

Having thus described my invention, what I claim as new, and desire to secure by Letters 75 Patent, is—

A car-coupling comprising a draw-head having an open upper side, a longitudinal slot in the lower wall thereof, bearings at the rear end of the draw-head for the support of the 80 coupling-pin when raised, a pivoted bar resting in said bearings and provided with parallel arms, and a coupling-pin pivoted between said arms and provided with an enlargement 85 intermediate its ends, and pivots thereon for engagement with the parallel arms, said enlargement being formed integral with the pin and adapted to rest on the link when in place, for the purpose and substantially as described. 90

In testimony whereof I affix my signature in presence of two witnesses.

ISAAC LOW.
